UNITED STATES PATENT OFFICE.

OLIVER J. BAILEY, OF FLORENCE, MASSACHUSETTS.

SILENCER FOR FIREARMS.

1,207,264.

Specification of Letters Patent.

Patented Dec. 5, 1916.

Application filed July 20, 1916. Serial No. 110,393.

To all whom it may concern:

Be it known that I, OLIVER J. BAILEY, a citizen of the United States, residing at Florence, in the county of Hampshire and 5 State of Massachusetts, have invented certain new and useful Improvements in Silencers for Firearms, of which the following is a specification.

This invention relates more particularly 10 to a device adapted to be attached to the muzzle of a fire-arm whereby the explosion occurring at the end of the muzzle will be smothered for preventing a report when the fire-arm is discharged.

15 One of the objects of the invention is to provide a structure which shall be adapted to be releasably mounted on the muzzle of a fire-arm and adapted to diminish the explosion regardless of the impact of the gases 20 as they escape from the barrel of the fire-arm, the construction being especially adapted to withstand great pressure.

A further object of the invention is the 25 provision of a plurality of diaphragms designed to divert the gases from the trajectory so that they may expand and be ejected from the rear of the casing in which the explosion occurs.

Another object of the invention is the 30 provision of an ejecting tube through which the gases are ejected for releasing and diminishing the pressure in the casing, the tube being designed to break up the hot gases as they pass through the tube whereby they may be 35 more quickly cooled and thus insure a noiseless exit at the end of the tube.

A further object of this invention is the 40 provision of a silencer for fire-arms which consists of comparatively few parts and is simple in construction, but durable and well adapted to withstand the rough usage to which devices of this character are ordinarily subjected.

For a full description of the invention 45 and the advantages and merits thereof, reference is to be had to the following description and the accompanying drawings, wherein is illustrated the preferred form of my invention, and in which—

50 Figure 1 is a fragmentary elevation of a rifle barrel partly in section, showing the silencer attached thereto. Fig. 2 is an end elevation of the silencer. Fig. 3 is a detail

sectional perspective of one of the wire gauze sleeves within the ejecting tube. 55

The rifle barrel A is of the usual formation and has the front "sight" B mounted adjacent its extreme forward end. Formed on the exterior of the rifle barrel at the end thereof is a plurality of screw threads which 60 are adapted to register with the screw threads formed on a coupling 1 which embraces the end of the rifle barrel A and is provided with a central opening through which the projectile passes when the fire-arm is discharged. Interposed between the coupling 1 and the end of the barrel is a gasket 2 which insures an air-tight joint at the end of the barrel of the fire-arm. Secured to the coupling and supported thereby 70 is the casing 3 which comprises an elongated member of pear-shape in cross section thus providing a large upper portion 4 and a relatively small lower portion 5. Thus two chambers, an expansion chamber 6 and 75 an ejecting chamber 7 are provided, the expansion chamber being considerably larger in diameter than the ejecting chamber. The longitudinal center line of the expansion chamber 6 is in alinement with the central 80 bore of the fire-arm and, therefore, the projectile passes directly through the longitudinal center of the expansion chamber 6. Each end of the casing is provided with an 85 opening through which the projectile passes when the fire-arm is discharged.

For diverting the gases from the trajectory into the ejecting chamber and also for reducing the explosion which occurs at the end of the rifle barrel, I provide a plurality 90 of diaphragms 8 which are substantially frusto-conical in formation and are provided with flanges 9 which are adapted to be attached to the inside of the casing 3. The diaphragms 8 are arranged in a series extending longitudinally through the casing and have their angularly disposed surface extending at an angle toward the front end of the casing so that the gases are diverted from the center of the casing while the projectile is passing through the casing. A central circular aperture is formed in each diaphragm for permitting the passage of the projectile. The frusto-conical shape of the diaphragms is especially desirable when the 100 heated gases cause the diaphragms to be 105

intensely heated, thus causing them to expand and retract as they are gradually heated and cooled. The expansion and retraction will not warp or disturb the diaphragms, their conical shape permitting them to expand and retract with the casing thus assuring an unobstructed path for the projectile through the casing.

Each diaphragm 8 is provided with a curved lip 10 which, as shown by Fig. 1 of the drawing, is curved rearwardly and its extreme lower edge is disposed at the longitudinal center of the ejecting chamber 7. Thus, when the gases are diverted by the diaphragms, the same will be led into the ejecting chamber and the pressure will cause them to seek an exit through the opening 11 at the rear end of the ejecting chamber 7. Integrally formed with the cylindrical portion 5 of the casing is an ejecting tube 12 the interior of which forms communication between the ejecting chamber and the atmosphere. By integrally forming the tube 12 at the longitudinal center line of the lower portion 5, the tube is disposed directly beneath the barrel A of the fire-arm. Arranged within the tube 12 is a plurality of wire gauze cylinders or sleeves 13. These cylinders or sleeves 13 are closed at each end. As shown by Fig. 1 of the drawing they are slightly spaced apart to provide a series of double foraminous walls through which the gases must pass when they are ejected through the tube 12. The wire gauze sleeves therefore, provide an efficient means for thoroughly breaking up and agitating the gases as they pass through the tube 12 so that when they reach the end of the tube their force is materially reduced and they are greatly cooled so that they enter the atmosphere noiselessly.

Mounted on the extreme end of the ejecting tube 12 is a wire gauze mantle 14 of cylindrical formation and having one end obstructed by the foraminous wall 15 and its opposite end open so that a portion of the mantle may extend over the end of the tube 12. A collar 16 is employed to fasten the mantle 14 to the tube 12. This mantle 14 is constructed of fine wire mesh or gauze and is adapted to assist the wire gauze sleeves 13 when the continued use of the fire-arm overtaxes the sleeves 13 and causes a slight report when the gases reach the atmosphere at the end of the ejecting tube. An absolutely noiseless discharge of the gases is thereby effected regardless of the number of times that the fire-arm is discharged.

From the foregoing it will be observed that a very simple and durable silencer for fire-arms has been provided, the details of which embody the preferred form. I desire it to be understood however, that slight changes in the minor details of construction may be made without departing from the

spirit of the invention or the scope of the claims hereunto appended.

I claim:

1. A silencer for fire-arms including a casing comprising superposed cylindrical portions having their interiors communicating to provide a silencing chamber and an ejecting chamber, and a plurality of frusto-conical diaphragms arranged independently of each other and secured within the silencing chamber and having their lower edges disposed above said ejecting chamber. 75

2. A silencer for fire-arms including a casing comprising superposed cylindrical portions having their interiors communicating to provide a silencing chamber and an ejecting chamber, and a plurality of frusto-conical diaphragms arranged independently of each other and secured within the silencing chamber and having their lower edges disposed above said ejecting chamber, the said silencing chamber opening into the atmosphere at the front end of the casing and the said ejecting chamber opening into the atmosphere at the rear of said casing. 80 85 90

3. A silencer for fire-arms including a casing comprising superposed cylindrical portions having their interiors communicating to provide a silencing chamber and an ejecting chamber, and a plurality of frusto-conical diaphragms arranged independently of each other and secured within the silencing chamber and having their lower edges disposed above said ejecting chamber, and a lip formed on each diaphragm and extending into said ejecting chamber. 95 100

4. A silencer for fire-arms including a casing comprising superposed cylindrical portions having hollow interiors to provide a silencing chamber and an ejecting chamber, a plurality of frusto-conical diaphragms arranged within the casing, each diaphragm being provided with a plurality of flanges secured to the interior of the silencing chamber, each end of the casing and the center of each diaphragm being provided with a circular opening in alinement with the longitudinal center of the silencing chamber, and a rearwardly curved lip formed on each diaphragm and having its edge disposed at the longitudinal center line of the ejecting chamber, the said casing being provided with an exit in its rear wall in alinement with the center line of the ejecting chamber. 110 115 120

5. A silencer for fire-arms including a casing comprising superposed cylindrical portions having hollow interiors to provide a silencing chamber and an ejecting chamber, a plurality of frusto-conical diaphragms arranged within the casing, each diaphragm being provided with a plurality of flanges secured to the interior of the silencing chamber, each end of the casing and the center of each diaphragm being provided with a circular opening in alinement with the longitudu- 125 130

- dinal center of the silencing chamber, a rearwardly curved lip formed on each diaphragm and having its edge disposed at the longitudinal center line of the ejecting chamber, the said casing being provided with an exit in its rear wall in alinement with the center line of the ejecting chamber, and an ejecting tube integrally formed with the casing at the rear wall thereof and having its interior 10 communicating with the said exit from the ejecting chamber.
6. A silencer for fire-arms including a casing having a silencing chamber and an ejecting chamber, a plurality of diaphragms arranged within the silencing chamber, means carried by the diaphragm for diverting the gases from the silencing chamber into the ejecting chamber, an ejecting tube integrally formed with the casing and extending rearwardly from the ejecting chamber, and means carried by the interior of the ejecting tube for agitating the gases as they enter the said tube from the ejecting chamber.
- 25 7. A silencer for fire-arms including a casing having a silencing chamber and an ejecting chamber, a plurality of diaphragms arranged within the silencing chamber, means carried by the diaphragm for diverting the gases from the silencing chamber into the ejecting chamber, an ejecting tube integrally formed with the casing and extending rearwardly from the ejecting chamber, and a plurality of foraminous sleeves disposed within the said tube and having their ends arranged in superposed relation to each other.
- 30 8. A silencer for fire-arms including a casing having a silencing chamber and an ejecting chamber, a plurality of diaphragms arranged within the silencing chamber, means carried by the diaphragm for diverting the gases from the silencing chamber into the ejecting chamber, an ejecting tube integrally formed with the casing and extending rearwardly from the ejecting chamber, a plurality of foraminous sleeves disposed within the said tube and having their ends arranged in superposed relation to each other, and means mounted on the end of the tube for further agitating the gases as they leave the tube.
- 35 9. A silencer for fire-arms including a casing having a silencing chamber and an ejecting chamber, a plurality of diaphragms arranged within the silencing chamber, means carried by the diaphragm for diverting the gases from the silencing chamber into the ejecting chamber, an ejecting tube integrally formed with the casing and extending rearwardly from the ejecting chamber, a plurality of foraminous sleeves disposed within the said tube and having their ends arranged in superposed relation to each other, a mantle constructed of foraminous

material mounted upon the end of the tube and a collar for securing the said mantle to the tube.

10. A silencer for fire-arms including a casing having a silencing chamber and an ejecting chamber, a plurality of diaphragms arranged within the silencing chamber, means carried by the diaphragm for diverting the gases from the silencing chamber into the ejecting chamber, an ejecting tube integrally formed with the casing and extending rearwardly from the ejecting chamber, a plurality of foraminous sleeves disposed within the said tube and having their ends arranged in superposed relation to each other, the end of each sleeve being provided with a foraminous wall whereby a series of double foraminous walls are provided when the said sleeves are assembled with the said tube.

11. A silencer for fire-arms including a casing comprising an expansion chamber and a relatively small ejecting chamber, and a plurality of frusto-conical diaphragms arranged within the said expansion chamber and having central openings longitudinally alined with each other and with the longitudinal center line of the said expansion chamber and a plurality of lips carried by the said diaphragms and having their edges terminating at the longitudinal center line of the said ejecting chamber.

12. A silencer for fire-arms including a casing having a plurality of diaphragms arranged therein, an ejecting tube integrally formed with the casing and communicating therewith, and a plurality of foraminous sleeves carried by the said tube.

13. A silencer for fire-arms including a casing, the said casing being pear-shaped in cross section to provide a large upper portion and a relatively small lower portion, a plurality of diaphragms arranged in the said large portion, and means carried by the diaphragms for diverting the gases from the said large portion of the casing into the small portion thereof.

14. A silencer for fire-arms including a casing shaped to provide relatively large and small chambers intercommunicating for their full length, a plurality of diaphragms arranged within the said large chamber and each provided with a plurality of flanges circumferentially spaced apart on the periphery of each diaphragm and adapted to be attached to the inside of the casing, and means formed by curving a portion of each of said diaphragms for leading the gases from the said large chamber into the said small chamber and directing their course toward the opposite direction from that in which they enter the said casing.

15. A silencer for fire-arms including a casing shaped to provide relatively large and small intercommunicating chambers, a

plurality of diaphragms arranged within the large chamber, and a rearwardly curved lip integrally formed with each diaphragm, the said casing having an exit provided at the rear of the said small chamber, the terminal of each curved lip being disposed in alinement with the said exit.

In testimony whereof I affix my signature in presence of two witnesses.
